US0D1056698S

(12) **United States Design Patent** (10) **Patent No.:** **US D1,056,698 S**
Hu (45) **Date of Patent:** **** Jan. 7, 2025**

(54) **SCREW WITH MOTOR FOR DRIVING AWAY ANIMALS**

(71) Applicant: **Shenzhen Visson Technology Co., Ltd.**, Shenzhen (CN)

(72) Inventor: **Guoqing Hu**, Shenzhen (CN)

(73) Assignee: **Shenzhen Visson Technology Co., Ltd.**

(**) Term: **15 Years**

(21) Appl. No.: **29/859,892**

(22) Filed: **Nov. 15, 2022**

(51) LOC (15) Cl. **08-08**

(52) U.S. Cl.

USPC **D8/387**; D22/120

(58) **Field of Classification Search**

CLAIM

The ornamental design for a screw with motor for driving away animals as shown and described.

DESCRIPTION

FIG. 1 is a front perspective view of a screw with motor for driving away animals, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

1 Claim, 7 Drawing Sheets
